SAFETY LOCK FOR TEXTILE MACHINE COVERS

Original Filed March 25, 1929

UNITED STATES PATENT OFFICE

1,987,563

SAFETY LOCK FOR TEXTILE MACHINE COVERS

Joseph Moss, North Smithfield, R. I., assignor, by mesne assignments, to Whitin Machine Works, Whitinsville, Mass., a corporation of Massachusetts

Original application March 25, 1929, Serial No. 349,697. Divided and this application March 18, 1932, Serial No. 599,701

7 Claims. (Cl. 192—135)

This invention forms a divisional part of my original application for U. S. Letters Patent, Serial No. 349,697, filed on March 25, 1929, for Cotton openers or pickers.

5 The present invention relates to locks for the doors or covers ordinarily provided in the housings surrounding dangerous moving parts of machines in general, and more particularly to safety locks for cotton preparing machinery, such 10 as openers and pickers, wherein especially operating parts such as beaters travel at such high speeds as to be inconspicuous or invisible to the eye, and hence constitute very grave hazards.

The main object of the present invention is to 15 provide locking means for cotton machinery which will permit convenient opening of the covers, doors or guards of enclosed operating parts when the machine is not running, but positively will prevent access to these parts of the machine 20 when these latter are in operation, and also will prevent starting of the machine when the covers or guards are in unlocked relation.

In the attempt to provide satisfactory safety 25 locks for such doors, covers, and guards, a variety of exacting conditions must be met. The devices must be simple and direct in their action, to make certain that they will work every time. They must be easy to operate, and impose no extra burden or nuisance on the operator, or he will 30 find a way to render them inoperative and subject himself to the hazard they are aimed to protect him from, just to simplify his work. They must not give access to the enclosed parts until the latter have actually come to rest, as serious 35 accidents have happened where the safety locks have been rendered inoperative as soon as the driving power is unshipped, and access thus allowed to the parts while still traveling under their own momentum. They must not rely wholly on 40 magnetism or gravity for their maintenance in a relation to prevent opening of the doors or guards, or on the force of springs with their propensity for failure without warning, or on friction when subjected to the vibration caused by 45 the running of the machine in question or adjoining machines, as is nearly always the case.

With the aim of satisfying these requirements, the invention comprises a wholly mechanical and positive safety lock which not only locks the cover 50 in closed position when the drive-shaft of the dangerous moving parts is in running relation, and correspondingly locks the drive-shaft against rotation before the cover can be raised, as heretofore in certain instances, but also locks the locking device itself in one or other of the positions 55

it assumes in effecting the reciprocal locking and release of these parts, so that it cannot shift or give way accidentally; and the said means may also be arranged so as to assume their control over the movement of the lock automatically. The device is simple and strong, comprising only two moving parts, and easy to make and fit and operate, the manipulations involved in its operation being performed simultaneously by the two hands of the attendant practically instantaneously and with a minimum need for care and attention. Preferably the whole locking mechanism is made as a unit which may be assembled in perfect working relation and thereafter quickly and easily installed in the machine in which it is to operate. Other aims and advantages are as will appear hereinafter.

An illustrative embodiment of the invention is shown in the accompanying drawing in which,—

Fig. 1 is a vertical section of the beater-chamber of a picker, showing the beater and parts co-operating therewith, the cover for such chamber, and the safety lock of the invention combined with the casing to engage the cover and the lock- 25

Fig. 2 is a view of certain of the parts of Fig. 1, viewed mainly in section on line 2—2 of Fig. 1.

The picker shown in part in Fig. 1 is of known construction, and includes a beater 1 fixed on a shaft 3 mounted in bearings in the housing or casing 5, and driven by a pulley 7 fixed on the shaft outside of the casing by a key 9. Access to the beater-chamber is had through a swinging flat cover or door 6, the free end 8 of which is lifted upwardly in opening it. Grid-bars 11, a feed-roll 13, an evener condenser cage 15, and evener-pedals 17 cooperate with the beater 1 in known manner to accomplish the feeding, opening, and cleaning of the stock.

In the embodiment illustrated herein, one of the slots in the casing through which the beater on its shaft is inserted in the beater-chamber and lowered into its bearings is occupied by a plate 21 forming the base of the locking unit or assembly, the lateral margins of which are received in rabbets formed between the vertical margins of the casing adjacent the slot and applied strips 23 which are attached to the casing by rivets 25, so that the plate 21 becomes a part 45 of the enclosing end-wall of the casing.

On the outward side of the plate 21 are formed bosses 27, in which are fixed pins 29, the reduced inward ends of which are headed over as indicated at 31 at the interior surface of each plate. 55

A slide 33 is mounted on these pins 29 for easy sliding movement toward and from the casing in a direction parallel to the axis of the beater-shaft 3, suitable holes or bearings being provided 5 in the slide to fit upon the pins 29. The portion 35 of the slide intermediate the two pins is rounded or otherwise appropriately shaped for grasping, so as to serve as a manipulating handle for the slide.

10 The driving pulley 7 is formed with one or more fins or vanes 37 immediately within its flange which are accessible from the side of the pulley confronting the casing and the plate 21. The lower end of the slide 33 is equipped with a finger 15 or projection such as the pin 39 screwed into the lower end of the slide illustrated in Fig. 2 which is adapted to enter the path of rotation of the projections or fins 37 in connection with the pulley 7 when the slide is slid outward in a direction away from the casing, and thus to prevent 20 the rotation of the driving wheel or pulley 7 and consequently prevent the revolution of the beater 1 within the casing. Where a plurality of fins 37 is provided, they will always be spaced amply 25 to permit easy and rapid insertion of the pin 39 between them when the beater and its pulley 7 are at rest.

At its upper extremity, the slide 33 is provided with a latch 41, pivoted in a cleft in the 30 slide by a pivot 43, and having a limited degree of angular movement about such pivot in a direction upward and away from the casing, the limit of such movement being set by the engagement of a tail 45 on the latch 41 outwardly of the pivot 43, with the outward side of the slide at the bottom terminus of the cleft in which the latch is mounted. The inward or free end of the latch overlies the lateral edge of the cover or door 6 which gives admission to the beater-chamber, in such manner that even when the 35 latch 41 is rotated about its pivot to the extent permitted by the tail 45 thereof, the latch will still continue to prevent the raising of the cover 6, so long as the slide remains in its inward position with the pin 39 clear of the path of rotation of the fins 37 on the pulley 7. It is only when the beater and its pulley have been brought to rest, so that the pin 39 can enter between the fins, that it will be possible to move outwardly 40 away from the plate 21 far enough to carry the latch 41 outwardly beyond the margin of the cover 6, leaving the latter free to be raised and permitting unimpeded entry into the beater-chamber. The beater will remain locked until 45 the slide is again moved inward to withdraw the pin 39 from the path of rotation of the projections on the pulley 7, which movement returns the latch to cover-locking position.

To maintain the slide against accidental shift, 50 and keep the locking mechanism either in a position in which the cover 6 is locked and the beater shaft free to rotate, or in a position in which the beater and its driving wheel 7 are positively locked against rotation and the cover 55 6 free to be opened, the latch is provided with a tooth or projection 47 to enter depressions or apertures 49, 51, formed in a lip 53 extending outwardly from the plate 21. When the tooth is in the inward aperture 49, the extremity of the latch overhangs the cover 6 and prevents its opening, and the slide 33 is itself locked against movement until the latch 41 shall have been tipped up into its dotted-line position in which the extremity of the tooth 47 is above the plane 60 of the top of lip 53. Similarly, when the slide is 70

in its outward position, with the pin 39 blocking rotation of the pulley 7, the latch 41, unless otherwise restrained, gravitates downward so that its tooth 47 enters the aperture 51, locking the slide in position to prevent all rotation of the beater shaft and beater so long as the latch 41 remains in a position in which the cover 6 can be opened. 5

The manipulation of the locking device is of the simplest order, requiring merely that the latch 41 shall be held lifted with one hand while 10 the slide is being shifted with the other.

Since the attainment of the proper operating speed for the beater 1 depends on the rate of rotation and diameter of the particular going part, in connection with the prime mover, from which power is taken and applied to the shaft 3, it is not always convenient to employ the periphery of the wheel 7 as the surface engaged by the belt; but instead of replacing the wheel 7 by a similar wheel of different diameter, it is usually simpler 15 as a practical mechanical resort to fix an ordinary pulley of proper size to the end of shaft 3 outward of the wheel 7 to receive the driving belt, leaving the wheel 7 undisturbed to perform its 20 described part in the locking operation. 25

While I have illustrated and described a certain form in which the invention may be embodied, I am aware that many modifications may be made therein by any person skilled in the art, without departing from the scope of the invention as expressed in the claims. Therefore I do not wish to be limited to the particular forms shown, or to the details of construction there- 30 of, but

What I do claim is:

1. In textile machines, the combination with a casing enclosing working parts thereof, a cover or the like movable for access to such parts, and a driving shaft for such parts, of a member locking the driving shaft against rotation and also freeing the shaft for rotation, a latch moving with the member into and out of the path of opening movement of the cover, and interengaging means on the latch and the casing to fix the latch in and out of the path of the cover and thus to maintain the member in shaft-locking or shaft-freeing relation. 35

2. In textile machines, the combination with a casing enclosing working parts thereof, a cover or the like movable for access to such parts, and a driving shaft for such parts, of a member movable into positions respectively locking the driving shaft against rotation and freeing the driving shaft, and a latch engaging a fixed part on the machine to maintain the said member in such positions, the latch also engaging the cover to prevent opening of the latter. 50

3. In textile machines, the combination with a casing enclosing working parts thereof, a cover or the like movable for access to such parts, and a wheel rotating always with such parts, of a slide, a member carried by the slide into locking engagement with the wheel, and a latch fixing the slide in positions in which the wheel is respectively locked and freed, the latch also engaging the cover to prevent opening the latter when the slide is in one position. 55

4. In textile machines, the combination with a casing enclosing working parts thereof, a cover or the like movable for access to such parts, and a wheel rotating always with such parts, of a slide movable parallel to the axis of the wheel, a member moving with the slide to lock the wheel against rotation, and a latch pivoted to the slide, tending to engage a fixed part of the machine. 60

to prevent movement of the slide, intercepting the cover to prevent opening of the latter whenever the said member is out of locking engagement with the wheel, and removable from engagement with such fixed part to permit movement of the latch out of the way of the cover.

5. In textile machines, the combination with a casing enclosing working parts thereof, a cover or the like movable for access to such parts, and 10 a driving shaft for such parts, of a slide having movably applied thereto a cover-locking latch which in the inward position of the slide engages and holds the cover closed, the slide having also a stop which is carried into rotation-preventing 15 relation with the driving shaft by movement of the slide outward to unlock the cover, the latch locking the slide in its respective positions.

6. In textile machines, the combination with a casing enclosing working parts thereof, a cover 20 or the like movable for access to such parts, and

a driving shaft for such parts, of a member locking the driving shaft against rotation, and a latch moving with such member and engaging the cover to prevent opening of the latter, and a fixed part on the machine having depressions with which the latch engages to prevent movement of the latch and the said member.

7. In textile machines, the combination with a casing enclosing working parts, a wheel rotating always with such parts, and a cover giving 10 access to the said parts, of a lock mechanism to be applied to the machine as a unit, comprising a base, a slide sliding on such base, a member on the slide preventing rotation of the wheel, and a latch pivoted on the slide and having a portion 15 engaging the base to hold the latch and slide from movement and a contiguous portion to intercept the cover and prevent opening of the latter whenever the member is free of the wheel.
